US00D832238S

(12) **United States Design Patent** (10) **Patent No.:** **US D832,238 S**
(45) **Date of Patent:** **** Oct. 30, 2018**

(54) **SPEAKER COVER**

(71) Applicant: **RB Distribution, Inc.**, Colmar, PA (US)

(72) Inventors: **Christopher Thomas Van Osten**, Souderton, PA (US); **Jessica Anne Miron**, Philadelphia, PA (US); **Eric Joel Tryson**, Willow Grove, PA (US)

(73) Assignee: **RB Distribution, Inc.**, Colmar, PA (US)

(**) Term: **15 Years**

(21) Appl. No.: **29/608,412**

(22) Filed: **Jun. 21, 2017**

(51) LOC (11) Cl. **14-01**

(52) U.S. Cl.

USPC **D14/219**

(58) **Field of Classification Search**

USPC ..... D14/219, 209, 204, 210, 215, 224, 240, D14/250, 258, 440, 138 AA, 194, 192, D14/249, 447, 225, 226; D23/412, 385, D23/371, 351, 393; 181/144, 146, 148, 181/150, 151, 171, 199; 379/450, 452; 381/380, 381; 455/90.1, 575.1, 569.1

CPC ... H04R 1/02; H05K 9/00; H05K 5/00; G10K 11/00; H04B 1/38

(57) **CLAIM**

The ornamental design for a speaker cover, as shown and described.

DESCRIPTION

FIG. 1 is a perspective view of the underside of our speaker cover;

FIG. 2 is a plan view of the underside of our speaker cover in FIG. 1;

FIG. 3 is a plan view of the top side of our speaker cover in FIG. 1;

FIG. 4 is a right side view of our speaker cover in FIG. 1; FIG. 5 is a left side view of our speaker cover in FIG. 1; FIG. 6 is a rear elevation of our speaker cover in FIG. 1; and, FIG. 7 is a front elevation of our speaker cover in FIG. 1. The broken line showing in the drawings is included for the purpose of illustrating environment and forms no part of the claimed design for our speaker cover.

1 Claim, 7 Drawing Sheets
